BICYCLE FRAME

John McGregor Gordon, Nuthall, Nottingham, and Harry Letherland, Brancote Hill, Nottingham, England, assignors to Raleigh Industries Limited, a corporation of Great Britain

Filed June 7, 1968, Ser. No. 12,255

Claims priority, application Great Britain Dec. 9, 1967

Term of patent 7 years

U.S. Cl. D90—8
Int. Cl. D12—11

FIG. 1.

FIG. 2.

FIG. 3.

FIG. 4.

FIG. 5.

FIG. 6.

FIG. 7.

FIG. 8.

FIG. 1 is a side elevation of our design of bicycle frame;

FIG. 2 is an inverted plan view of the bicycle frame shown in FIG. 1;

FIG. 3 is a perspective view of the frame shown in FIGS. 1 and 2;

FIG. 4 is a rear elevation of the said frame;

FIG. 5 is a side elevation of a modified form of our design;

FIG. 6 is an inverted plan view of the bicycle frame shown in FIG. 5;

FIG. 7 is a perspective view of the second embodiment; and

FIG. 8 is a rear elevation of the frame shown in FIG. 5. We claim:

The ornamental design for a bicycle frame, as shown and described.
